FLUSH LEVER

Fred M. Keller, Grand Rapids, Mich.

Application March 26, 1949, Serial No. 83,741

1 Claim. (Cl. 4—67)

1

This invention relates in general to a single action, flush handle assembly including a flush lever and particularly to a type thereof mountable as a pre-assembled unit on the side wall of a flush tank.

Considerable and vigorous experimental efforts have been directed toward the development of a flush handle assembly representing the maximum in simplicity and consequent minimum cost of fabrication, while maintaining a high level of operating efficiency, sturdiness of structure and smartness of appearance. However, no flush handle assembly completely satisfying these demands up to now is known to have been made.

Accordingly, a primary object of this invention is to provide a single action flush handle assembly in which the working parts are reduced to a minimum and yet in which there is maintained a high level of operating efficiency, sturdiness of structure and pleasing appearance.

A further object of this invention has been to provide a single action flush handle assembly, as aforesaid, which is simple to manufacture and pre-assemble as well as being easy to install by unskilled persons.

Other objects and purposes of this invention will become apparent to persons familiar with this type of equipment upon referring to the accompanying drawings and upon reading the following specification.

In meeting those objects and purposes heretofore mentioned, as well as others incidental thereto and associated therewith, I have provided a cylindrical mounting fixture having an integral, circumferential flange near one end thereof, said fixture being provided with external threads near the other end thereof. The mounting fixture is also provided with a cylindrical, coaxial chamber therethrough having a portion of reduced internal diameter near the end thereof remote from said circumferential flange. A flush handle is provided with a head having an integral sleeve extending therefrom and rotatably receivable into said cylindrical chamber at the end thereof adjacent said flange. The circumferential flange is provided with a lug near the outer radial edge thereof which extends in a direction parallel to the axis of said chamber toward said handle head. A pair of spaced integral bosses are provided on said handle head for cooperating with said lug for limiting the rotational movement of the handle with respect to the mounting fixture.

A flush lever is provided with a perpendicularly disposed, integral shank portion near one end thereof, which shank portion is rotatably sup-

2

ported within the reduced portion of said cylindrical chamber and is secured at its free end within the said sleeve of said handle. Means, including a nut threadedly cooperable with the threaded portion on said fixture is provided for securing the said fixture within an appropriate opening in the side wall of a flush tank.

For illustration of a preferred embodiment of the invention attention is directed to the drawings in which:

Figure 1 is a broken, top plan view of the flush handle assembly to which this invention relates, including a broken line fragment of the side wall of a flush tank.

15 Figure 2 is a broken, side elevation view of said flush handle assembly.

Figure 3 is a sectional view taken along the line III—III of Figure 2.

Figure 4 is a sectional view taken along the line 20 IV—IV of Figure 2.

Figure 5 is an end elevation view of the outer end of said mounting fixture.

Figure 6 is a sectional view taken along the line 25 VI—VI of Figure 4.

Construction

The terms "inner" or "inwardly" and "outer" or "outwardly" as used in this specification will be understood to mean "upwardly" and "downwardly," respectively, with respect to Figure 1 as well as "inwardly" and "outwardly" with respect to the flush tank side wall, the inside of said side wall being indicated by the letter A in Figure 1.

30 The flush handle assembly 10 (Figures 1, 2 and 3) is comprised of a mounting fixture 11, a handle 12 and a flush lever 13. The mounting fixture 11 has a substantially cylindrical body 14 which is provided with external threads 15 near the inner end of the fixture body. The outer end of the fixture body 14 is provided with a circumferential, integral, preferably cylindrical and coaxial flange 16 which is substantially larger in its external diameter than said fixture body. That portion 17 of the fixture body between the threads

35 15 and the flange 16 preferably has an out of round cross-section, such as square. The side wall 18 of the flush tank (Figure 1), upon which said flush handle assembly 10 is mounted, is preferably provided with an out of round opening 19 conforming with the out of round portion 17 of the mounting fixture 11, thereby preventing rotation of the mounting fixture with respect to the tank side wall 18 when said fixture is inserted completely into and through said open-

40 50 55 ing 19.

A nut 22 (Figure 1) is provided for threaded cooperation with the external threads 15 on the mounting fixture body 14, for securing the flange 16 against the tank side wall 18. A lug 23, which is preferably integral with the cylindrical flange 16, extends from the outer face 36 of said flange adjacent to the radially outer edge thereof in a direction substantially parallel with the axis of the fixture 11. The purpose of the lug 23 will be described in detail hereinafter.

The fixture body 14 is provided with a cylindrical chamber 24 extending therethrough and having a bearing portion 25 of reduced internal diameter adjacent to the inner end thereof, thereby providing a lever supporting opening 26.

The handle 12 (Figures 1, 3, 4 and 6), of any ordinary die-cast metal capable of taking and holding a press fit as hereinafter described, is provided with a head 27 at one end thereof, said head having a recess 28. The handle head 27, which has a substantially circular outer rim 29, is provided with an integral sleeve boss 31 coaxial with said circular rim 29 and extending out through the center of the head recess 28 substantially beyond the plane of said head rim 29. The outside diameter of the sleeve boss 31 is preferably slightly smaller than the inside diameter of the cylindrical chamber 24 in the fixture body 14, thereby permitting rotatable support of the boss 31 by the walls of said chamber 24. A cylindrical shank recess 42 is provided coaxially within said sleeve boss 31.

A pair of stop bosses 32 and 33 (Figure 6), which are preferably integral with the head 27, are positioned within the head recess 28 between the head skirt 34 and the sleeve boss 31. The free edges 35 (Figures 3 and 6) of the stop bosses 32 and 33, against which the outer face 36 of the cylindrical flange 16 bears, are preferably spaced inwardly of said head recess from the said plane of the head rim 29. The stop bosses 32 and 33 are spaced for reception of the lug 23 therebetween when the free edges 35 of the stop bosses are bearing against said flange outer face 36. The rotation of the handle 12 with respect to the mounting fixture 11, when the sleeve boss 31 is operably supported within the cylindrical chamber 24, is controlled both by the size of the lug 23 and the spacing between the bosses 32 and 33.

The lever 13 (Figures 1, 2, 3 and 4), made from any ordinary brass capable of taking and holding a press-fit connection as hereinafter described, is comprised of an arm portion 37 and a rocker shank 38 near one end of said lever and perpendicularly disposed thereto. The free end 41 of the shank 38 is received into the coaxial, cylindrical shank recess 42 in the sleeve boss 31, which recess is preferably slightly larger in diameter than said shank 38 in this embodiment of the invention. The respective diameters of the shank 38 and the recess 42 will vary according to the materials being used, but will follow ordinary press-fit practices which are well known and therefore do not require detailed description. The extremity of said free end 41 may be rounded to facilitate its entry into the recess 42.

The outer end 41 of the rocker shank 38 is preferably distorted, as by means of the knurling 43 (Figure 3), for the purpose of increasing the size of the shank 38 and thereby effecting a securing between said shank 38 and the side walls of said cylindrical recess 42 without fracturing the sleeve boss 31.

The opposite end of the shank 38 near the arm

portion 37 is rotatably supported within the lever opening 26. Thus, the shank 38 is rotatably supported within the cylindrical chamber 24 near the inner end thereof by means of the bearing portion 25 and near the outer end 41 thereof being held within the sleeve boss 31.

A bead 44 is pinched upon, and is integral with, the shank 38 at a predetermined distance from the outer end 41 thereof, said bead being designed to limit the outward, axial movement of the rocker shank 38 with respect to the mounting fixture 11, by bearing against the inner face of the bearing portion 25. This bead is preferably pinched onto said shank prior to its assembly 15 with the handle.

The lever arm 37 (Figure 2) may be provided with a plurality of openings 45 therethrough remote from the shank 38 for engagement by an appropriate flush valve, not shown, of any conventional type.

Operation

The flush handle assembly 10 is assembled by inserting the sleeve boss 31 into the outer end of the cylindrical chamber 24 and inserting the rocker shank 38 through the lever opening 26 and the outer extremity of its free end 41 into the opening of the cylindrical shank recess 42 in the sleeve boss 31. Sufficient pressure is then exerted in a conventional manner to force the knurled portion 43 of the shank 38 into said recess 42 and effect a tight press-fit therebetween. The shank end 41 is inserted into the opening 42 sufficiently to effect a firm engagement between said shank and the boss 31 but preferably not to the bottom of the recess 42 in order to provide normal manufacturing tolerances due to possible variations in the length of the shank and/or the depth of the recess 42. These tolerances must be provided so that the bead 44 can be properly spaced from the stop bosses 32 and 33.

When the lever 13 and handle 12 are thus securely fastened together, the bead 44 limits outward axial movement of the lever 13 and handle 12 with respect to the mounting fixture 11. The stop bosses 32 and 33 in the head recess 28, which bosses bear against the flange outer face 36 on the mounting fixture 11, limit inward axial movement of said lever and handle with respect to the mounting fixture 11. The relative positioning of all of these parts is, in the light of the foregoing, obviously such as to permit free rotation of said handle and shank with respect to said fixture but holding said shank and handle against material axial movement with respect to said fixture. The oscillatory movement of the lever shank 38 and handle 12 with respect to the fixture 11, is confined within the limits imposed by the lug 23 on the fixture 11 and the stop bosses 32 and 33 on the handle 12. The bearing portion 25 and sleeve boss 31 which rotatably support the lever shank 38 within the cylindrical chamber 24 are positioned remotely from each other to provide two spaced bearing points for the purpose of preventing any wobble of the flush handle assembly during operation.

The flush handle assembly 10 may be mounted on a flush tank side wall 18 of any convenient, conventional type and in a substantially conventional manner, as shown in Figure 1. The mounting fixture 11 is inserted through an appropriate opening 19 in the tank side wall 18 until the flange 16 is firmly against the outside of said tank side wall. The nut 22 is threaded onto the threads 15 on the inner end

of the fixture body 14 and brought up tightly against the inside surface A of the tank side wall 18. An appropriate flush valve (not shown) of any conventional type may be suspended in a conventional manner, such as shown in my application Serial No. 679,031 (issued as Patent No. 2,468,203, April 26, 1949), upon the flush lever arm 37 by means of the arm openings 45 therein.

Although the above mentioned drawings and description apply to one particular, preferred embodiment of the invention, it is not my intention, implied or otherwise, to eliminate other variations or modifications which do not depart from the scope of the invention unless specifically stated to the contrary in the hereinafter appended claim.

I claim:

A single action flush handle assembly mountable upon a flush tank side wall having an opening therethrough, comprising in combination: a substantially cylindrical mounting fixture extending through said tank opening and having a circumferential, integral, radially outwardly extending flange exterior of said tank with a lug extending axially therefrom near the radially outer edge thereof, said fixture having a coaxial, cylindrical chamber therein and a bearing portion having a cylindrical opening therethrough communicating with said chamber and of reduced internal diameter with respect thereto; 30 means exteriorly engaging the interior end of said fixture for securement thereof to said tank; a handle having a head with a cylindrical sleeve

extending therefrom and rotatably supported within the exterior end of said chamber; a pair of spaced bosses on the inside of said head facing said flange and near said sleeve cooperating with said lug to limit the rotation of said handle and engaging said flange for spacing said head from said flange; a lever having a perpendicular disposed cylindrical shank portion near one end thereof, the extremity of said one end being non-rotatively secured within said sleeve; and a point on said shank portion spaced from said extremity being rotatably supported within the opening in said bearing portion and a bead on said shank portion adjacent to the interior end of said fixture for limiting the outward axial movement of said shank portion with respect to said fixture.
